ROLLER RAIL UNIT

Henry H. Harris, Champaign, Ill.

Application November 16, 1937, Serial No. 174,776

3 Claims. (Cl. 193—35)

My invention relates generally to industrial heat treating furnaces, such as carbonizing furnaces and the like, and specifically relates to the means employed within the furnace on which to move articles therethrough.

Articles to be heat treated are usually loaded onto flat-bottomed supports, such as trays, boxes or the like. These supports are disposed on top of skid rails or tracks or on various types of roller rails and are then pushed through the furnace in tandem. The flat skid rails have been found to be unsatisfactory, both because of the destructive effects of the friction generated by the flat-bottomed supports, and because of the injurious effects of the heat conditions within the furnace which, with the load bearing stresses, cause warping, buckling and bending of the rails.

Ordinarily, roller rails, that is, rails on which rollers are mounted, while not subject to the destructive effects of travelling friction to the same extent as are flat skid rails, are nevertheless subject to the injurious effects of furnace heat and work support and travel thereover, and are so formed that usually the entire roller rail must be replaced if any part thereof becomes worn or damaged through use. This is an expensive operation, and among the objects of my invention, therefore, is the provision of a roller rail unit comprising a shell having a number of independently replaceable axle and roller units secured therewithin.

A further object of my invention is the provision of a roller rail unit made up of relatively few and easily replaceable parts.

Other and related objects of my invention will in part be pointed specifically, and in part be obvious from the following description of an illustrative embodiment.

In the drawing annexed hereto and made a part hereof:

Figure 1 is a plan view of one form of roller rail unit constructed according to and embodying my invention;

Fig. 2 is in part a side elevational view and in part a longitudinal sectional view; and

Fig. 3 is an enlarged transverse sectional view on the line 3—3 of Fig. 2.

Reference numeral 10 indicates my improved roller rail unit which comprises a substantially hollow cylindrical shell 12, having formed therein a number of bosses 14, 14, in which axles or pins 16 are secured, about which axles or pins 16 rollers 18 are mounted for rotation, the upper portions of the rollers 18 projecting upwardly of the shell 12 through a slot formed in the top thereof

permitting work supports to be moved upon the rollers.

Shell 12 comprises an elongated, generally cylindrical hollow member which is preferably formed as a casting of heat and corrosion resisting alloy, of nickel, chromium and iron composition. The casting can be made in one piece or in two pieces, and welded together as indicated at 19. A plurality of pairs of transverse, horizontally opposed, and inwardly directed apertured bosses 14, 14, are formed as an integral part of shell 12, the pairs being spaced at equal distances apart within the hollow interior of said shell 12. A longitudinal roller slot 20 is formed at the top of shell 12 extending the full length thereof, the width of slot 20 being equal to the distance between opposed bosses 14, 14, and slot 20 being longitudinally aligned with the space between said bosses. As stated, shell 12 is cylindrical and the opposing, spaced-apart apertured bosses 14, 20 14 project inwardly from the side walls, with the space between the bosses and the slot width being equal. A channel is thus formed in shell 12 within which rollers 18 are placed.

Rollers 18 are preferably formed as one-piece castings of heat and corrosion resisting alloys, preferably of nickel, chromium and iron composition, as are axles or pins 16, which comprise short lengths of hollow cylindrical tubing, as shown in Figs. 2 and 3. Alloys having high wear resisting qualities as well as being resistant to heat and corrosion are preferably used for these parts. Roller 18 is formed of such thickness that when inserted into the interior of shell 12 through slot 20 and the hub 22 thereof aligned with the apertured bosses 14, 14, and kept in such position by axle or pin 16, which passes through the apertured bosses and the hub opening 22, sufficient clearance is left between the bosses 14, 14, and the sides of slot 20 so that roller 18 will rotate freely in such position. Roller 18 is of such diameter with respect to the height of shell 12, that when secured in the position shown in Fig. 3, the top of the roller will project above the top of the shell, as indicated at 50, in order that work supports can be moved through the furnace over the rollers.

The slot 20 may be covered, if desired, at those regions between the projecting portions of roller 18, as by means of plates 36 welded into slot 20, as indicated at 38, thereby keeping the inside of the shell relatively free of scale or other material which might clog the action of the rollers. Holes 38 in shell 12 and holes 36 in rollers 18 permit entering materials to drop out and also 55

allow access to the interior of the rollers and the shell for cleaning purposes.

Axes or pins 16 are secured within shell 12 as by welded connections 30, but any convenient connection may be made. With the axles or pins 16 fixed within the bosses 14, 14, rollers 18 are free to rotate thereon, and the wear and friction is divided up between the roller hub and the axle or pin, the weight of the furnace load being distributed over the roller, axle or pin, the bosses and shell walls.

To form a continuous roller rail, a number of my elongated units 10 are placed end to end, with the rollers upwardly, and extending the length of the furnace within which same are to be secured, and are locked in such relation by being placed within feet 32 secured on the furnace floor, or on elevated track or platform (not shown). Feet 32 are so shaped on the under side thereof as to rest flatly on the supporting structure, and have openings into which are received the flared walls 34 of shell 12 to secure adjacent units together and to keep same from twisting or rolling out of alignment. Shells 12 are secured within feet 32 as by a welded connection, indicated at 40, although if desired, any convenient connection may be made.

As stated above, rollers 18 and shell 12 are cored, as at 36 and 38, to provide for self cleaning or to permit access to the interiors of these members for cleaning. If desired, sufficient clearance may be provided between the floor of shell 12 and roller 18 to allow for any accumulation of scale which might occur during use. This would avoid the necessity for cleaning.

My improved roller rail unit has numerous features of advantage. For one thing, the parts are simple and can be cast at very low expense. For another thing, maintenance cost is low, and the parts can be assembled, taken down and replaced easily and inexpensively. For instance, if any particular axle or pin becomes damaged or worn,

only that particular pin need be replaced to restore the entire unit to operating efficiency, and the time and expense of a complete replacement thus obviated.

Having now described my invention, what I claim and desire to secure by Letters Patent is:

1. A roller rail unit for use in heat treating furnaces comprising an elongated, hollow, cylindrical member having a slotted top and a plurality of opposed and spaced apart inwardly extending apertured bosses therewithin formed as an integral part thereof, pins passing through and supported by said bosses, and rollers supported by said pins for rotation about said pins between said bosses and upwardly through said slotted top.

2. A roller rail unit comprising an elongated, hollow cylindrical member having a longitudinal slot in the top thereof, a plurality of opposed and spaced apart apertured bosses formed within the hollow member, the space between said bosses being equal to the width of the longitudinal slot and aligned therewith, a plurality of rollers disposed within the hollow member, pins passing through said bosses and said rollers and providing journals for said rollers, and the upper portions of said rollers extending through the slotted top of the hollow member.

3. A roller rail for use in heat treating furnaces comprising an elongated hollow cylindrical shell having a longitudinal slot in the top thereof, a plurality of pairs of apertured and spaced apart bosses within the shell defining a roller channel therebetween substantially equal to the width of the slot, a plurality of rollers within the shell, each of which is disposed between and aligned with a pair of bosses, a plurality of axles passing through said rollers and bosses, said rollers being mounted for rotation about said axles, and means to secure the shell against rotary movement,

HENRY H. HARRIS.
